UNITED STATES PATENT OFFICE.

HAROLD EUGENE CARPENTER, OF SEWICKLEY, PENNSYLVANIA, ASSIGNOR TO RITER-CONLEY MANUFACTURING COMPANY, OF JERSEY CITY, NEW JERSEY, A CORPORATION OF NEW JERSEY.

CHARGING AND DRAWING MACHINE FOR GAS-RETORTS.

No. 880,440.

Specification of Letters Patent.

Patented Feb. 25, 1908.

Application filed May 22, 1905. Serial No. 261,632.

To all whom it may concern:

Be it known that I, HAROLD EUGENE CARPENTER, a citizen of the United States, residing at Sewickley, in the county of Allegheny and State of Pennsylvania, have invented a new and useful Improvement in Charging and Drawing Machines for Gas-Retorts, of which improvement the following is a specification.

10 My invention relates to improvements in gas retort charging machines, and the object of my invention is to provide such machines with means to enable the operator to control the movement of the machine along the bench of retorts; also the movements of the hopper charging and drawing mechanism, so as to bring them upon the level of the various retorts readily and without changing his position during such movements, and to accomplish this purpose my invention consists in providing the machine with a platform for the operator, secured to the frame of the charging and drawing mechanism; and a series of vertically disposed rods connected to and corresponding in number with levers which control the movements of the machine and its various parts enumerated, and hand levers slidable upon said rods, whereby the operator is enabled to occupy relatively the same horizontal plane with the charging and drawing mechanism and control the movements thereof and of the machine along the bench of retorts by means of the operating levers slidable on said rods; and to more readily observe the operation of the charging and drawing mechanism.

I will now describe my invention, reference being had to the accompanying drawings, forming part hereof, in which—

40 Figure 1 is a side elevation of a charging machine with my improvement applied thereto. Fig. 2 is an end elevation of the same. Fig. 3 is a detail view of one of the operating levers. Fig. 4 is a fragmentary view on an enlarged scale of the operating levers and the rotatable rods with which said levers are associated, the dotted lines indicating the slidable relation of the levers to said rods.

50 Like reference characters indicate like parts wherever they occur.

Referring to said drawings, A represents the charging machine, which is mounted on

wheels 1 and adapted to travel on rails 2, 2, along the bench of retorts 3. The said machine is provided with an upright frame, 4, and a truck 4', to which said frame is secured, and on which the operating mechanism is mounted.

55 5 is a motor adapted to propel or cause the machine to travel along the bench of retorts, also for elevating and lowering the hopper 6 and the charging mechanism frame to the various levels of the retorts as hereinafter described: The said motor is provided with a shaft 7, upon the outer end of which is mounted the worm 8, which engages with and transmits power to the worm gear 9 mounted upon the upper end of the vertical shaft 10 on which is loosely mounted the bevel gear 11; the said bevel gear 11 meshes with and transmits power to the gear wheel 12 which is mounted on the transverse shaft 13, which is journaled in bearings formed in a portion of the frame 4 and the upright 14. 75 A worm 15 is mounted upon said shaft and meshes with and transmits power to the worm wheel 16 which is mounted on the shaft 17. The said shaft 17 is journaled in bearing formed in the blocks 18 which are secured to the frame 4 and the upright 14, and has mounted thereon the drum 19, over which the chains 20, 21 pass and are adapted to be wound for the purpose of elevating and lowering the hopper 6 and the charging frame 22, which is secured to the lower end of said hopper, the opposite ends of said chains, respectively, being anchored or attached to the sides of the hopper frame at the top thereof as shown in Fig. 2. The said chain 20 passes from the drum 19 to the pulley 23, which is mounted in bearings 24 secured in the frame near the bottom thereof, thence to and over the pulley 25 to the pulleys 26, 27, and 28 and is finally secured to the upper side of the hopper frame at x. The chain 21 passes over pulleys similar in construction and similarly located and disposed in the opposite end of the frame and is anchored to the same at a point opposite to x. 100

Upon the lower end of the vertically disposed shaft 10 is loosely mounted the miter gear 29, which meshes with the beveled gear 30 secured upon one of the axles of the machine, and when the clutch member 31 which is integral with said miter gear 29 is engaged

by the clutch 32 and thus rigidly secured to said bevel gear 29 on said shaft 10, transmits power to said bevel gear 30 on the axle of the machine, and propels said machine along the 5 said retorts. The motor or ram 33 which is mounted in the rear end of the charging mechanism frame 22, through the medium of which the forward and backward movement of the charging mechanism is obtained, is 10 actuated by the lever 34. The feeding scoop of the charging mechanism is controlled by the wheel 35. As the mechanism for advancing the charging device is not involved in the present invention, I will not more fully 15 describe the same.

Heretofore, so far as I am aware, the movements of the apparatus herein described were controlled by levers accessible to the operator only when he occupied the truck or 20 platform of the machine, requiring him to descend from the charging frame of the apparatus in order to manipulate the same. In other words the movements of the machine and the charging apparatus carried 25 thereby were controlled by levers operable only from the truck of the machine, requiring the operator to remain thereon in order to control the movements of the various mechanisms, and making it impossible for 30 him to closely observe the operation of the charging device.

It is the primary object of the present invention to obviate these difficulties, and to do so I provide the machine with a platform 35 36, which is secured to the frame of the charging machine and upon which the operator remains during all the various movements of the machine and of the mechanism carried thereby and from which he has easy 40 control of all the levers which actuate the machine. A series of operating levers 37, 38 and 39 are pivotally attached to the plate 40 which is secured to the frame of the charging apparatus at a point thereon relative 45 to said platform 36, which enables the operator on said platform to readily control said levers at all times. The said levers are connected to a corresponding number of vertically disposed rods 41, 42 and 43, which 50 are rotatably secured in bearings, formed in the brackets 44 and 45, which project from and are secured to the sides of the frame of the machine, the said levers 37, 38 and 39 being, respectively, connected to said rods 55 41, 42 and 43, by means of splines 45', whereby when either of said levers are operated they cause the rods to which they are respectively connected to rotate or turn thereby operating the controlling levers to which 60 said rods are respectively connected, and permits these rods to slide upon said splines as the charging mechanism frame is elevated and lowered. The said rod 41 is connected to the counterweighted lever 47, which is 65 connected to and actuates the clutch 32 by

means of the link 48 and the lever 49, to which it is connected. The lower end of the rod 42, is connected to a link 50, which is connected to the vertical rod 51, the upper end of which is provided with a bevel wheel 52, which meshes with and transmits movement to the wheel 53 on one end of the transverse shaft 54, the opposite end of which is connected to the vertical link 55, which is pivotally connected to the link 56 which is 70 connected to and actuates the valve 57 which controls the admission of air to the motor. The lower end of the rod 43 is connected to the link 58 which is connected to and actuates the hand brake 59 to apply the 75 same when the said rod is rotated by the hand lever connected thereto. A vertically disposed rod 60 is mounted in the brackets 44 and 45 and on the lower end thereof is mounted the spring pressed blocks 61, 62, 80 the lower one of which is adapted to contact with the lever 63 when the charging frame arrives at its lowest point. The said lever 63 is connected to and actuates the link 64, which is pivotally attached to the link 65, 85 the upper end of which engages the shaft 54, and through the links 55-56 operates the valve to reverse the motor. Motive fluid is admitted to said motor through the supply pipe 66, which enters the upper end or top 90 of the valve casing 67, in which a valve is located to control the admission of motive fluid to reversing valve 57 of the motor by means of pipe 68.

"I claim as my invention and desire to secure by Letters Patent:

1. In a machine for charging and drawing gas retorts, the combination of a vertically-movable frame carrying the charging and drawing mechanism, a platform attached to 105 said vertically-movable frame and movable therewith, and means in proximity to the platform to operate the machine and charging and drawing mechanism from said platform.

2. In a machine for charging and drawing gas retorts, the combination of a movable frame adapted to carry the drawing and charging mechanism, a platform, a plate secured upon said frame near said platform, 115 levers pivotally secured to said plate, rotatable rods upon which said levers are slidably, and means to connect said rods with the operating levers.

3. In a machine for charging and drawing 120 gas retorts, the combination of a movable frame carrying the charging and drawing mechanism, a platform secured to said frame, a series of levers pivotally connected to the frame near the platform, a series of vertically disposed rotatable rods upon which said levers are slidably mounted, and means to connect the operating mechanism of the machine with said rods.

4. In a machine for charging and drawing 125

gas retorts, the combination with a movable frame carrying the charging and drawing mechanism, of a platform attached thereto and movable therewith, mechanism to operate the machine and drawing mechanism, and means associated with said mechanism for actuating the same from said platform, said means being shiftable with the change of position of the platform without disturbing their operative relation to the mechanism

for operating the machine and drawing mechanism.

In testimony whereof I have hereunto signed my name in the presence of two subscribing witnesses.

HAROLD EUGENE CARPENTER.

In the presence of

CLARENCE A. WILLIAMS,
JOHN H. RONEY.
